UNITED STATES PATENT OFFICE

GEORGE A. SPILLER AND GEORGE T. JOHNSON, OF COLUMBUS, OHIO, ASSIGNEES TO THE
BUCKEYE STEEL CASTINGS COMPANY, OF COLUMBUS, OHIO

DOOR

Application filed December 18, 1928. Serial No. 326,823.

The present invention pertains to doors, and especially to drop end doors for open end freight cars of the gondola type.

It is customary to make such doors of built-up construction, and it is known to those conversant with such matters, that such doors have some very weak points. The type of car with which such doors are employed, is becoming more widely used, and is almost invariably of the largest capacity; namely, 70 tons, and they are loaded with all kinds of heavy bulk material, including pipes and other rolling mill products, and all such lading has a tendency to shift when the cars are bumped around in service; and the shifting of the load throws considerable strain upon the end doors, which in view of the fact that they are separate movable pieces, are not of a construction best suited for resisting such forces. As a result, the end doors bend or bulge outwardly at the top, indicating that the pressed steel doors of the conventional design are not as rigid as would seem to be necessary. The bottom of the door, being toed against a door abutment that is secured to the end sill of the car, is kept in alignment for a while, but as said abutment is formed of a relatively light sheet metal upturned lip, extending the full width of the car, and is not very strong; due to corrosion and rough usage, the vertical lip of the abutment becomes bent, and allows the door to also bulge outwardly at the bottom.

The main purpose of the present invention is to furnish a metal door which, while of the lightest possible construction, commensurate with the strength required, will withstand the strains to which such doors are subjected, without being buckled or distorted.

A further object is to provide a freight car door having a channel shaped border designed on three sides to abut against the sides and floor of the car, to increase the stability of the door.

With the foregoing objects set forth, and with additional objects which will appear as the description proceeds, the invention consists in the novel features hereinafter described in detail, illustrated in the accom-

panying drawings, and specifically pointed out in the annexed claims.

Referring to the drawings,

Fig. 1 is an elevation of the improved door, viewed from its inner side. 55

Figs. 2 and 3 are vertical sectional views of the same, taken on lines 2-2 and 3-3 respectively, of Fig. 1.

Fig. 4 is a plan view, looking toward the upper edge of the door. 60

Figs. 5, 6 and 7 are longitudinal, horizontal sectional views taken respectively on lines 5-5, 6-6 and 7-7 of Fig. 1.

Fig. 8 is an elevation of the door, viewed from its outer side and showing a modification. 65

Fig. 9 is an enlarged elevation of a detail of the door shown in Fig. 8.

Fig. 10 is a vertical sectional view on line 10-10 of Fig. 8. 70

The improved door is of unitary construction, and formed of one piece of metal, preferably cast, and shaped to provide the requisite stability. 75

1 designates the main web or wall, bordered by an angular flange 2, which provides a channel shaped reinforcement at each edge of the door. As best shown in Fig. 1, this flange, at the upper end of the door, extends downwardly in the form of a depending skirt 3, which is of greatest depth at its middle 4, and is gradually tapered from this point toward the ends of the door. The flange makes the edge portion of the door extremely rigid, and the deepening of the part 3 provides increased reinforcement at the top of the door, which must resist the greater strain. 85

Vertical ribs 5 are provided on the inner face of the door, and each of these ribs merges into the main web 1, the flange 2, and the apron 3, and each rib is gradually tapered toward the main web near its lower end, as shown at 6. 90

A main horizontal rib 7 extends the full length of the door, and its ends merge into the side flanges at the points 8. 95

These intersecting vertical and horizontal ribs are also provided with integral reinforcing flanges 9, which merge into the inner 100

extensions of the flanges 2, and the flanges on each vertical rib 5 are integrally united with the main web, as shown at 10.

The lower central portion of the door is reinforced by a shorter horizontal rib 11, having tapered end portions terminating short of the ribs 5, and the rib 11 is also reinforced by oppositely extending flanges 12 that merge into the web 1. The ribs and their reinforcing flanges may be looked upon as T-shaped reinforcements.

As doors of this type are used in close proximity to the brake wheels at the ends of the car, the metal of the web is shaped as shown at 13, to provide a pocket into which the brake wheel may project and allow clearance for the hands of the operator.

Apertured ears 14 are arranged in pairs near the lower side of the door to form parts of the hinges employed in pivotally connecting the lower side of the door to the floor of the car.

By way of reiteration, it may be noted that the top edge of the door has a channel construction for increased strength, and the apron 3 has been made widest at the center where the greatest strength is needed. The vertical and horizontal intersecting ribs 5 and 7 stiffen the door as a whole, and the vertical ribs are tapered toward the bottom, where they are least needed. The tapered horizontal intermediate rib 11 is designed to stiffen the surrounding area of the main web 1 against local bulging, and the internal flange all around the edges of the door enables substantial bearing to be taken along three of its sides. Due to this, the main horizontal rib 7 may be located nearest the top edge of the door. This main rib and the nearby channel at the top edge, will eliminate bending at and near the top of the door.

As the door forming the subject matter of this invention was designed especially for use with a car end of the type shown in application Serial No. 322,284, filed November 27, 1928, it need not be as rigid at its lower end as at its upper end, for a heavily reinforced abutment of the cast steel car end will prevent bulging along the bottom edge.

The casting may be made with holes 15 at each end near the upper corner of the door to receive the rivets employed in connecting the latch links to the door, or as shown in Figs. 8, 9 and 10, the door may be provided at these points with latch hooks 16 which are integral portions of the casting that forms the door. Each hook is formed by an upwardly extending arm 17 reinforced by a flange 18. With this construction, the latch links may be mounted on the sides of the car, and then the latches can engage the hooks for locking the door in upright position at the end of the car.

It is believed from the above description that the construction and advantages of the

invention may be readily understood, and it is manifest that changes may be made in the structure disclosed without departing from the spirit of the invention as expressed in the claims.

What we claim and desire to secure by Letters Patent is:

1. A one-piece metallic freight car door including a main web provided at its edge with an integral angular flange, whereby the edge of the door is of channel shape, the edge of said flange being inturned, said flange having continuations forming intermediate horizontal and vertical reinforcements for the web.

2. A freight car door including a metallic web provided with an endless angular flange at its edge, said flange being integral with the web and extending around the entire edge of the door, the edge of said flange being inturned.

3. A freight car door including a metallic web provided at its upper edge with an integral angular flange having an apron as part thereof, said apron tapering from its medial portion toward the ends of the door.

4. A one-piece metallic freight car door including a main web provided around its entire edge with an angular flange, whereby the edge portion of the door is of channel shaped cross section, and reinforcing ribs for the door integral with said flanges.

5. A one-piece metallic freight car door including a main web provided around its entire edge with an angular flange, and substantially T-shaped reinforcements on one face of the web merging into said flanges.

6. A one-piece metallic freight car door including a main web, and a substantially angular flange forming a border for said web, and integral with the latter, the edge of said flange being inturned, and said flange having continuations forming intermediate horizontal and vertical reinforcements for the web.

7. A one-piece metallic freight car door including a main web, a substantially angular flange bordering said web and integral with the latter, the edge of said flange being inturned, and reinforcing ribs extending along and integral with said web, portions of said ribs being formed by continuations of the inturned edge of said flange.

8. A one-piece metallic freight car door including a main web, intersecting T-shaped ribs integral with said web, the end of one of said ribs being tapered and merging into the web.

9. A one-piece metallic freight car door including a main web, substantially T-shaped reinforcements integral with the web and intersecting at one side thereof.

10. A one-piece metallic freight car door including a main web, a substantially angular flange bordering the web and integral with the latter, the edge of the flange being in-

turned, and intersecting ribs arranged on one face of the web, integral with the latter and having certain of their ends merging into said border flange.

6 11. A one-piece metallic freight car door including a main web, a substantially angular flange bordering said web and integral with the latter, a horizontal T-shaped rib extending along a face of the web between its upper 10 and lower edges, and having its ends merging into said border flange, and a pair of vertical T-shaped ribs intersecting the horizontal rib, arranged on opposite sides of the medial portion of the door, and having certain 15 of their ends merging into said border flange.

12. A one-piece metallic freight car door including a main web, a substantially angular flange integral with the web and forming a border for the latter, and substantially vertical ribs arranged on one face of the web and having their upper ends merging into said flange, the lower end portion of each rib tapering toward the web and terminating 25 above the lower edge of the door.

13. A one-piece metallic freight car door including a main web, a flange forming a border for the web and integral with the latter, and a substantially horizontal T-shaped rib arranged on one face of the web and having its ends tapering toward and merging into the web.

14. A one-piece metallic freight car door including a main web, a substantially angular flange integral with the web and forming a border for the latter, the upper portion of said flange including a depending skirt tapered from its medial portion toward its ends, a horizontal rib, arranged on one face 35 of the web and having its ends merging into said flange, vertical ribs positioned on one face of the web, on opposite sides of the medial portion of the same, each of said vertical ribs merging at its upper end into 40 said flange, and having its opposite end tapered toward and merging into the web, and an intermediate horizontal rib positioned 45 below the first mentioned horizontal rib and located between said vertical ribs, the intermediate rib having its ends tapered and merging 50 into the web.

15. A freight car door including a main metallic web provided at its opposite end portions with integral latch receiving hooks.

55 16. A freight car door including a main metallic web provided at its opposite end portions with integral latch receiving hooks, each hook being provided with a reinforcing rib that is integral with the hook and web.

60 In testimony whereof, we have signed this specification.

GEORGE A. SPILLER.
GEORGE T. JOHNSON.
